UNITED STATES PATENT OFFICE.

FRANK H. GIBBS AND ERNEST FRED DODSON, OF PORTLAND, OREGON.

ELECTRICAL-CONDUCTOR CONNECTION.

Application filed December 11, 1923. Serial No. 679,996.

This invention relates to improvements in electrical conductor connections, having for an object to provide a connector especially advantageous for use in conjunction with telephones, whereby a freely rotatable connection may be made between the translating apparatus of the phone and the phone stand proper, thus preventing twisting of the wires and inconvenience to a user of the 10 phone, as well as stressing the conductors.

It is likewise an object of the invention to provide a connector of the character mentioned utilizing a novel form of electrical contacts, capable of free rotary motion without 15 out, in any way whatsoever, interrupting or interfering with the electrical intelligence transmitting circuits.

Other objects of the invention will be in part obvious and in part pointed out herein- 20 after.

In order that the invention and its mode of operation may be readily understood by persons skilled in the art, we have in the accompanying illustrative drawings, and in 25 the detailed following description based thereon, set out one possible embodiment of the same.

In these drawings:-

Figure 1 is a top plan view of the improved connector showing the casing removed;

Figure 2 is a vertical transverse section therethrough, taken on the line 2-2 of Figure 1 looking in the direction in which the 35 arrows point and with the casing thereon; and,

Figure 3 is a detail in perspective of the conductor outlet tube.

Having more particular reference to the 40 drawings, in connection with which like characters of reference will designate corresponding parts throughout, the improved connector may be stated to comprise a base 1 formed of insulating material, such as fibre 45 or the like, having apertured ears 2 extended from the opposite side portions, as shown in the Figure 1, while a forwardly disposed extension or lip 3 having a thickened portion 4 is formed upon another of the sides 50 thereof and serves as means for receiving contact plates generally indicated by the numeral 5, such plates being secured in position upon the upper face of the thickened portion 4 in equi-distant relation through 55 the medium of screws 6, or similar fastening devices, while conductor securing terminals

7, 8 and 9 are arranged upon the various contact plates 5 and secured thereto by passing bolts 10 through the same and the adjacent portions of the thickened portion 4; 60 locking nuts 11 being turned into engagement with the screw threaded extremities of said bolts, as shown in the Figure 2.

Concentrically arranged circular tracks of different diameters, indicated by the numerals 12, 13 and 14 are formed in the upper face of the base 1 and receive therein copper, or other electrically conductive rings, generally indicated by the numeral 15, such rings 15 resting upon the bottoms of the various circular tracks or ways 12, 13 or 14 and having spring fingers 16 secured to the upper sides thereof and extending above the same whereby to yieldably support other copper or other electrically conductive rings, generally indicated by the numeral 17, these latter contact rings being arranged in proximity to the open upper ends of the various ways 12, 13 and 14, as is shown in the Figure 2.

A cap comprising a body portion formed of insulating material corresponding to that of the base 1 and indicated by the numeral 18 is provided the connector and has circular ways formed in the under side thereof and arranged in concentric fashion and is indicated by the numerals 12', 13' and 14', such ways being so arranged in the bottom face of the cap 18 as to coincide with the arrangement of the ways 12, 13 and 14 respectively. 90 Copper or other electrically conductive contact rings generally indicated by the numeral 19 are arranged within the various ways 12', 13' and 14', while spring fingers 20 are arranged adjacent their outer faces and serve to yieldably receive other copper or suitably electrically conductive contact rings 21 thereon, as is shown in the Figure 2. Thus, it will be understood that the contact rings 17 and 21 are yieldably received 95 within their respective ways, 12, 12', 13, 13', 14 and 14'.

Loosely and rotatably positioned between the adjacent faces of the base 1 and the cap 18 is a disc 22 formed of fibre, or other suitable insulating material having a plurality of slots or ways cut or otherwise formed therein, such slots or ways serving to loosely receive and retain copper or other electrically conductive rollers 23 therein, the peripheral portions of which contact directly with the adjacent portions or faces of the contact

rings 17 and 21, thus electrically connecting such contact rings as well as the rings 15 and 19 which are connected thereto through the medium of the spring fingers 16 and 20.

- 5 To rotatably connect the cap 18 to the base 1, a headed pivot pin 24 is passed through a bearing opening located concentrically of said cap and said base, as shown in Figure 2, the lower end of the pivot pin 10 being received in a pocket 25 formed in the under side of the base 1 and being locked with relation thereto through the medium of a locking pin 26 passing through the lower end of the pivot pin and having the 15 opposite extremities thereof engageable with a washer or similar device 27 arranged in said pocket and over the extended end of the pivot pin 24. Preferably, anti-frictional bearings, mounted in suitable race ways or 20 keepers indicated by the numeral 28 are arranged in the upper portion of the cap 18 and receive a bearing washer 29 thereon, which washer in turn, receives adjacent portions of the head of the pivot pin 24. Thus, 25 free rotation of the cap 18 with respect to the pivot pin 24 as well as the base 1 is ensured.

Electrical conductors 30, 31 and 32 are extended from the contact plates 5 upon the 30 thickened portion 4 of the base 1 into engagement with portions of the contact rings 15 arranged in the circular ways 12, 13 and 14, while contact terminals 30', 31' and 32' are arranged upon the upper side of the 35 rotatable cap 18 and are connected to the contact rings 19 through the medium of electrical conductors 33.

The electrical conductors of the intelligence transmitting circuits of a telephone 40 equipped with the improved connector are adapted to be connected to the contact terminals 7, 8, 9, 30', 31' and 32' and in order that those portions of the conductors connected to the terminals 30', 31' and 32' may 45 be properly led from the connector, we provide a tubular member 34, forming the same of fibre or other suitable insulating material and providing it with a flanged basal portion 35 having openings 36 formed therein, 50 whereby when said basal portion is positioned upon the circular cap 18 directly over the pivot pin 24, locking screws 37 may be passed therethrough into engagement with the screw threaded openings formed in adjacent portions of said cap 18. Hence, the 55 tubular member 34 will be rigidly secured in its position upon the cap 18. The lower portion of the tubular member, together with its flanged basal portion 35 is formed with 60 a slot or way 38, through which the conductors led into engagement with the device are passed and then properly distributed for connection to their contact terminals 30', 31' and 32' in a suitable manner.

65 A circular or substantially cylindrical

casing or shield 39 is provided the connector and is adapted to be engaged therewith in the manner shown in Figure 2, the lower portion of said casing being secured in position upon the base 1 through the medium of suitable locking screws 40, while the upper constricted end thereof is provided with an opening 41 through which the upper portion of the tubular member 34 extends.

We also find it preferable to employ a 75 clamping screw in connection with the tubular member 34 whereby to prevent the application of stress to the conductors passing through said tubular member 34 and especially, to the conductors at their points of 80 connection with the contact terminals 30', 31' and 32' and in this direction, a circular band 42 is provided, being snugly arranged about the lower portion of the tubular member 34 adjacent the way 38 formed therein 85 and carries thereon a laterally extending lock 43 provided with a screw threaded opening through which a clamping screw 44 formed of suitable insulating material may pass. The inner end of this screw is adapted 90 to be turned through the way 38 into engagement with adjacent portions of the electrical conductors passing through the tubular member 34 and when so engaged, it will 95 be understood that the application or pull to the conductors at points adjacent their connection with the contact terminals 30', 31' and 32' will be avoided and hence, the 100 effecting of a positive electrical connection at these points will be at all times secured.

In using the improved connector, the basal portion is suitably fixed or secured to an object through the medium of the apertured ears 2, screws or other fastening devices being passed through the openings in such ears into engagement with the receiving object. Leads or conductors are then extended from the terminals of the translating apparatus of the telephone into engagement with the contact terminals 7, 8 and 9, whereupon they are secured to the same by adjustment of the bolts 10. Those conductors extending from the phone stand proper now have the free ends thereof 110 passed through the tubular member 34 from the way 38, whereupon they are properly connected to the various contact terminals 30', 31' and 32', their arrangement corresponding with the arrangement of the leads 115 from the translating apparatus of the telephone to the terminals 7, 8 and 9. The housing 39 is now arranged in position upon the connector, whereupon the device 120 is ready for use, it being understood that the conductors passing through the tubular member 34 have been properly engaged by the clamping screw 44 for the prevention of stress upon the conductors at the points of 125 their connection with their respective contact terminals.

Because of the electrical connection between the various contact rings 15 and 17 and 19 and 21 through the medium of the spring pressed fingers 16 and 20 and the various contact rollers 23, it will be understood that electrical circuits through the various conductors will be permitted and furthermore, that with rotation of the cap 18 upon the base 1, such electrical circuits will in no way be interrupted or interfered with, since the various contact rollers 23 will at all times remain in positive contact with their respective contact rings, this condition being rendered positive by reason of the yieldable seating of the contact rings 17 and 21 in their respective ways. Thus, it will be understood that the wires leading from the connector directly to the phone stand proper may be turned or rotated without possibility of their twisting and serving to inconvenience a user of the phone or possibly, stress the conductors to such an extent as to rupture the same or in some way interfere with the transmission of electrical intelligence thereover.

Manifestly, the construction shown is capable of considerable modification and such modification as is within the scope of our claim, we consider within the spirit of our invention.

We claim:—

A device of the character described comprising a base, electrical contact terminals

on said base, the upper face of said base having a plurality of circular concentrically arranged ways formed therein, contact rings arranged in said ways, other contact rings arranged in said ways, spaced from and yieldably supported with relation to said first contact rings and electrically connected thereto, a cap rotatably mounted upon said base, the lower side of said cap having a plurality of circular concentrically arranged ways formed therein corresponding to the ways formed in the adjacent face of said base, contact rings arranged in said ways formed in the cap, other contact rings arranged in said last mentioned ways spaced from and yieldably positioned with respect to the first contact rings received therein and electrically connected thereto, contact terminals arranged upon the cap, means for electrically connecting all of said contact rings to their respective contact terminals, circuit closing means movably arranged between the adjacent portions of said base and cap and engaging with the adjacent contact rings, and a tubular conductor receiving member rigidly supported upon the upper central portion of said cap and having a way formed in the lower portion thereof.

In witness whereof we have hereunto set our hands.

FRANK H. GIBBS.
ERNEST FRED DODSON.
